LOG-GRIPPING AND CENTERING SAWMILL DOG ASSEMBLY

Claude W. Wallace, Columbia, Miss.

Application September 20, 1944, Serial No. 554,967

1 Claim. (Cl. 143—128)

1
The present invention relates to new and useful improvements in dogs or holding apparatus for logs particularly adapted for holding logs firmly against movement in saw mills while being sawed.

The principal object of the present invention is to provide a power operated dog adapted to utilize fluid pressure such as steam for power.

Another important object of the invention is to provide a gripping dog for holding logs in saw mills which will not only firmly grip a log but quickly release the same when it is desired to move the log into a new position or release the same entirely.

In the drawings:

Figure 1 is a top plan view of the assembly.

Figure 2 is a side elevational view.

Figure 3 is an enlarged detailed sectional view showing gripping jaws with a portion of one in section.

Figure 4 is a section taken substantially on the line 4—4 of Figure 3.

Figure 5 is an elevational view of the drive rod connected jaw.

Figure 6 is a fragmentary detailed sectional view taken on the line 6—6 of Figure 3.

Figure 7 is a sectional view showing the dog assembly engaging a log and a saw cutting through the log, said saw being shown in broken lines.

Referring to the drawings wherein like numerals designate like parts, it can be seen that the dog assembly consists of a pair of elongated channelled members 5, 5 held in spaced and secured relation by interposed U-shaped members 6 bolted or riveted in place as at 7.

Spanning one end portion of the thus constructed bed is a steam cylinder 8 having foot portions 9 bolted or otherwise secured as at 10 to the top flanges of the channelled members 5.

In the cylinder 8 is a piston 11 from which a rod 12 extends through one end of the cylinder and pivotally connects by way of a bifurcated block 13 to a link bar 14, the block 13 being provided with a slide collar 15 operating on a guide bar 16 supported by bridge members 17 spanning the channelled members 5, 5.

Numeral 18 denotes a reversing valve to which a steam supply pipe 19 connects, this pipe having a cut-off valve 20 therein.

A rotary shaft 21 is provided for reversing the valve 18 and this has a hand-bar 22 at its outer end. A steam exhaust pipe 23 leading from the cylinder has a cut-off valve 24 therein.

The dog assembly itself as shown in Figure 3

2
consists of a pair of arcuate jaws 25, 26 provided with teeth 27 at the opposed sides thereof.

The lower portion of the inner faces of the jaws 25, 26 are provided with teeth 28 which mesh so that the operation of the jaw 25 results in concurrent operation of the jaw 26.

The outer intermediate portion of the jaw 25 is slightly reduced as at 29 to accommodate a knuckle 30 at the adjacent end of the link bar 14. The knuckle 30 is interposed between a pair of ears 31, 31 and a pin 32 is disposed through these ears and the knuckle 30 for pivotally connecting the link bar 14 to the jaw 25.

The jaws 25, 26 are pivoted on pins 33 suitably mounted between the channelled members 5, 5 (see Figure 4).

It can now be seen, that when the handle 22 is properly operated, steam will be admitted to the cylinder 8 while moving the piston 11 in one direction or the other. If the piston is moved toward the right in Figure 2, the jaws will be brought together to firmly grip a log or other object interposed. By again operating the handle 22, the valve 18 can be reversed and the steam or other fluid power is utilized for retracting the jaws so that the log or other object can be moved to a new position or entirely displaced from the dog assembly.

Figure 7 shows a saw 35 and a guide block 36 thereon, the saw 35 being shown in the act of cutting through a log 37.

While the foregoing specification sets forth the invention in specific terms, it is to be understood that numerous changes in the shape, size and materials may be resorted to without departing from the spirit and scope of the invention as claimed hereinafter.

Having described the invention, what is claimed

40
In a dog assembly for holding logs in sawmills, a bed of two spaced firmly connected channels, a pair of coacting jaws with interengaging teeth, for equal opposing angular gripping motion on both sides of the log, and with opposing gripping teeth for holding a log, said jaws having their lower teeth carrying portion interposed between said channels, said lower portion being fulcrumed on the channels near one end thereof,

45
a steam cylinder for operating the jaws fixed upon the bed formed by the channels near the other end of the latter, said steam cylinder having a working piston and piston rod, operating in substantial parallelism to said bed, a link connection between said piston and one of said jaws

UNITED STATES PATENTS

3

a guide bar for said piston rod and for one end of said link connection on said bed, and valve means arranged above the cylinder for admitting steam to the one or other side of the piston.

CLAUDE W. WALLACE.
